ATTORNEY

UNITED STATES PATENT OFFICE.

NORMAN A. McMEEKIN, OF WOODSVILLE, NEW HAMPSHIRE.

TOOL.

1,266,510.

Specification of Letters Patent. Patented May 14, 1918.

Application filed March 14, 1916. Serial No. 84,158.

To all whom it may concern:

Be it known that I, NORMAN A. McMEEKIN, a citizen of United States, residing at Woodsville, in the county of Grafton and State of New Hampshire, have invented certain new and useful Improvements in Tools, of which the following is a specification.

It is an object of this invention to provide a tool or implement which is adapted for 10 use in the household, or by campers, or the like, and which combines in a convenient manner a number of useful devices.

I attain the above and other objects by means of the construction and combination 15 of the various parts described which will be hereinafter more fully described and pointed out in the appended claims.

In the drawings:

Figure 1 is a side elevation of my device, 20 a portion thereof being shown in section.

Fig. 2 is a front elevation of my device.

Referring to the drawings by numerals 1 indicates a straight handle, and 2 indicates a curved handle which is continued in a reverse curve, as at 3, across the handle 1, said curved handle terminating in the jaw 4 which lies opposite the jaw 5 formed by the extended end of the handle 1. The handle 2, it will be noted, is pivoted to the handle 1 at the point of crossing by a rivet 6, both of said handles 1 and 2 being cut away adjacent the point of crossing, as at 1' and 2', so that their faces may lie in the same plane.

As clearly shown in Fig. 1, the jaw 4 of 35 the handle 2 lies opposite the jaw 5 of the handle 1. A flexible gripping member 7 is secured to the jaw 5 of the handle 1, as at 8, said strap adapted to be passed around the cover of a pail, or the like, for a purpose 40 which will hereinafter appear, and has its free end adapted to pass through an aperture 4' provided in the jaw 4 and be releasably held by means of serrations 9 adapted to co-act with a toothed pawl 10. It will 45 be seen by moving the handle 3 and the handle 1 toward each other that the jaws 4 and 5 will be caused to approach each other thereby tightening the flexible gripping member 7 around the pail cover.

Upon referring to the drawings, it will be noted that a bar 11 is pivotally connected by the rivet 6 to the handle 1 and is normally disposed along the face of the handle 1 in order to be out of the way. As shown in 5 dotted lines in Fig. 1, the said bar 11 is adapted to be swung upon the pivot 6 there-

by causing the end 12 thereof to engage the pail cover for a purpose which will be later referred to. A crown bottle top remover 12' is formed in the end 12 of the bar 11 and is 60 adapted to be used to remove bottle caps.

In Fig. 2, it will be seen that, the handle 1 is provided centrally thereof with a cut out portion 13 in which a cork screw 14 is adapted to normally lie in parallel relation 65 to the handle 1, the said handle 1 being further provided upon one end thereof with a can opener 15.

In operation, it will be apparent that, by grasping the device and moving the handle 70 1 and the handle 2 toward each other that the jaws 4 and 5 will be caused to approach each other, thereby tightening the flexible gripping member 7 around the pail cover, and by swinging the bar 11 upon the pivot 6 75 until the end 12 thereof engages the top of the pail cover, as shown in dotted lines; it will be seen that by lifting up upon the device that the said end 12 will exert leverage upon the pail cover, whereby the same may 80 be removed from the pail.

While, it is apparent from the above description taken in connection with the drawings, that I have provided a device which is efficient for the operation described, I do 85 not claim the exact construction shown therein but reserve the right to resort to certain minor changes and alterations which will not depart from the spirit and scope of the appended claims. 90

I claim:

1. A tool of the character described including handles, a flexible strip carried by one handle and engaging the other handle for embracing a pail cover, and a plate movably associated with one of said handles for engagement with the top side of the cover for exerting a leverage thereon. 95

2. A tool comprising handles pivoted together, jaws formed by said handles beyond the point of pivot, a flexible band secured to one of said jaws, the second of said jaws having an aperture formed therein through which the free end of said flexible band is adapted to pass, and means pivoted within 100 said aperture to grip said band between said means and the roof of said aperture when the handles are gripped and moved toward each other, in order to contract said band around a pail cover, and means to exert leverage upon the pail cover. 110

3. A tool comprising a straight handle

and a curved handle pivoted together in crossed relation, jaws formed on the handles by extending the straight handle and reversibly curving the curved handle beyond 5 the point of pivot, a flexible band having one end rigidly secured to one of said jaws, the free end thereof looped and adapted to pass through an aperture formed in the second of said jaws, a toothed pawl pivoted in said 10 aperture, adapted to co-act with teeth in the roof of said aperture to grip said flexible band against movement when the handles are gripped and moved toward each other, in order to contract said band around 15 a pail cover, or the like, and means pivoted at the point of pivot of the handles to exert leverage upon the pail cover.

4. A tool comprising a straight handle and a curved handle pivoted together in crossed relation, jaws formed on the handles by extending the straight handle and reversibly curving the curved handle beyond the point of pivot, a flexible band having 20 one end rigidly secured to one of said jaws, the free end looped and adapted to pass 25 through an aperture formed in the second of said jaws, a toothed pawl pivoted in said aperture adapted to co-act with teeth formed

in the roof of said aperture to grip said flexible band against movement when the handles are gripped and moved toward each other, in order to contract the said band around a pail cover, or the like, and a bar pivoted at the point of pivot normally lying adjacent one face of the straight handle so as not to project beyond the jaw, said bar 30 adapted to be swung on the pivot to project beyond said jaws to exert leverage upon the pail cover.

5. A tool of the character described, including crossed handles, a flexible strip secured to one of said handles, the other handle having an opening extending transversely through one end thereof, the end of said handle forming a roof for said opening, 40 and a pawl pivotally secured in the opening and co-acting with the roof portion thereof, to clamp the free end of said strip which is adapted to be passed through said opening.

In testimony whereof I affix my signature 45 in presence of two witnesses.

NORMAN A. McMEEKIN.
